Attorneys.

UNITED STATES PATENT OFFICE.

WILLIAM SCHOOF, OF MILWAUKEE, WISCONSIN.

CARBURETOR.

Application filed January 10, 1920. Serial No. 350,597.

To all whom it may concern:

Be it known that I, WILLIAM SCHOOF, a citizen of the United States, residing at Milwaukee, county of Milwaukee, and State of Wisconsin, have invented new and useful Improvements in Carburetors, of which the following is a specification.

This invention relates to improvements in carburetors for internal combustion engines.

- 10 One object of this invention is to provide a carburetor that will maintain a substantially constant mixture for all settings of the throttle valve and for all engine speeds with or without load. I am aware that certain 15 authorities have advanced the proposition that a substantially constant mixture is not desirable under all conditions. Ordinarily, however, where this opinion is advanced and any reason is assigned for it, the reason given is based upon charts of engine performance in tests involving determinations of the fuel consumption as compared with the brake horse power output of such engines. It can be shown that charts of performance derived 20 through the above method are fallacious in that at the higher ranges of speeds and at the lower ranges of speeds the work done by an engine can not accurately be ascertained by a brake horse power test. It can be 25 shown that an internal combustion engine running at comparatively high or at comparatively low speeds does work other than that exerted through the brake and that therefore the apparent output of work at the brake 30 becomes comparatively lowered at such speeds with reference to the amount of fuel consumed, thus causing the charts of performance to assume the peculiar curve upon which the opinions above referred to are 35 most often based. For this reason and because theoretically a constant mixture of fuel and air should give constant results in work output under all conditions of engine operation, I prefer to provide a carburetor adapted 40 to maintain a substantially constant mixture in so far as such a mixture is possible to obtain in practice. To provide such a carburetor is the principal object of this invention. 45 A further object is to provide a carburetor with means for temporarily and substantially instantaneously augmenting the supply of fuel for a sudden opening of the throttle valve and decreasing the supply of fuel for a sudden closing of the throttle valve. The 50 temporarily operative means above referred to is not intended to change, nor does it

change, the substantially constant mixture which it is my principal object to attain; on the contrary, the function of the means above mentioned is to maintain the mixture constant under circumstances such as might tend to alter the proportion of fuel and air. 60

A further object is to provide a carburetor which will improve the economy of operation. 65

A further object is to provide a carburetor with means for aiding in starting the motor.

A further object is to provide a carburetor in which the throttling, the augmenting or decreasing of the supply of fuel, and the aiding of the starting of the motor are all obtained by mechanism under a single lever control. 70

A further object of this invention is to provide a carburetor in which the mixture under normal carburetor operation will be entirely dependent upon air flow through the carburetor. It will not be affected by such factors as changes in engine speed or load or by changes in engine design, whereby within 80 its effective capacity the carburetor of my invention may be used with various types of engines under various conditions without adjustment.

It is a further object of this invention to 85 provide a carburetor which will not only operate to produce a substantially constant mixture but will also produce an ideal mixture such as is adapted to enable an internal combustion engine to give a maximum work 90 output in proportion to the amount of fuel supplied thereto, and whereby an excess of fuel will not be supplied at either high or low engine speeds, and an engine using a carburetor of this design will not become 95 overheated through the combustion of fuel in excess of that required for engine operation.

In the drawing:

The figure is a vertical sectional view 100 through the carburetor.

The carburetor comprises a main casing which is formed primarily of three members, 1 the upper portion, 2 the central portion, and 3 the lower portion of the carburetor. 105 The upper portion 1 may be secured to the portion 2 in any desired manner, as, for example, by bolting the flanged portions (not shown) together. The casing has an air inlet duct 4 which communicates with the 110 slightly enlarged upper portion 5 of the part 1. This portion 5 communicates with a low-

er portion 5' which has a slightly contracted upper portion 5''. This arrangement is formed to steady the mixture when the speed of the engine falls and the throttle valve is open. It has long been known that the flow of gases through orifices in thin plates follows a definite law, and that the co-efficient of discharge of such orifices, within certain limits as to size, becomes greater for high velocities of flow than for low velocities. The openings 17 are such as to operate under the aforesaid law so that their co-efficient of discharge is greater for high velocities of air flow than for low velocities. I have found by experiment that the velocity of flow through the openings 17 can be further modified by the provision exterior to said openings of the restricting wall 5'', and by actual tests I have determined that at low air speeds the relative efficiency of air flow into the carburetor from opening 17 is less when the restricting wall 5'' is present than it is in the absence of said wall. The presence of the wall does not, so far as I have been able to determine, affect the flow of air in the relatively higher ranges of air speed. The result, therefore, of the provision of the wall portion 5'' is apparently to increase the variation in the co-efficient of discharge which the openings 17 have in the absence of said wall. The delivery duct 6 through which the combustible mixture passes to the engine is formed in the central portion 2 and communicates with the substantially cylindrical opening 7. The portion 2 has a cylindrical casing 8 which extends downwardly within the portion 3. Within the cylindrical portion 8 is seated the fuel delivery nozzle 9 which has shoulders 10 bearing upon cooperating shoulders formed upon the cylindrical portion 8. A fitting 11 is screwed upon the lower portion of the nozzle 9 and extends downwardly through the bottom part of the portion 3 and is adapted to receive a nut 12 which when screwed into place, retains the casing 3 in position. The upper portion of the nozzle 9 is formed with a plurality of V-shaped projections 13 which form between them V-shaped notches 14. The entrance to the notches 14 is bevelled, as the tops of the projections 13 slope downwardly toward the center.

The throttle valve is a one piece structure and is adapted to control the flow of gases at two points between which the fuel is adapted to be supplied. It will be seen from the drawings and from the following description that the throttle valve controls both the air and the outgoing mixture. This throttle valve comprises a main cylindrical portion 15 which is provided with an integral top 16 and which is further provided along its cylindrical walls with a series of substantially triangular openings 17. This cylindrical member 15 slides within the cylindri-

cal portion 18 of the central member and upon its downward travel serves to close the openings 17 at a varying rate as such openings pass the upper edge of the portion 18. This is due to the inverted triangular shape of the openings 17, for, as is apparent from the drawings, the first portion of the openings to be closed is adjacent the apex, which is a relatively small area for a given distance of downward travel of the throttle valve. However, as the throttle valve continues on its downward travel, a greater and greater area per unit travel of the throttle valve is closed off. This throttle valve is slightly contracted towards its lower part and is provided at the lower end with a second cylindrical portion 19 which is adapted to slide over the projections 13 of the fuel supply nozzle and to close such openings to varying extents. The operating mechanism for this throttle valve consists of a rack 20 and gear segment 22, the rack being formed upon the pin 21 which is bolted to the top 16 of the throttle valve. The gear segment 22 is fast upon a shaft 23 which shaft extends outwardly through the upper side portion of the carburetor and is operated by means of a lever 24 which is adapted to be connected to one of the controls.

The casing 3 is adapted to form the main temporary reservoir for the gasoline, the height of which in such casing is controlled by means of a float 25 which operates a valve 26 through the medium of the pivoted lever 27. The valve 26 is provided with a double lower conical surface, the major part of which is ground at an angle of about 45° and the upper portion which seats upon the valve seat is ground at an angle of about 30° with the axis of the valve spindle. The valve spindle comprises a reduced portion 27' with a lower shoulder 28 and an upper shoulder 29 formed thereon between which works the rounded portions 30 of the forked lever 27. The upper portion of the valve spindle may be fluted and made heavy enough to partly balance the float 25. It is reduced at 31 so as to provide an extreme upper shoulder 32. This shoulder is adapted to be engaged by a portion of the shaft 33, the other half of which is cut away adjacent the shoulder 32. This shaft 33 extends outwardly beyond the fitting 34 and is adapted to be operated by a manually controlled lever 35. The fitting 34 is clamped in position by a machine screw passing through the opening 34' in a split portion of the casing 3. The gasoline inlet 35 for the carburetor communicates with a cylindrical cavity 36 into which is screwed a fitting 37, the upper walls 38 of which are adapted to hold a gauze filter screen 39 in place. The filter screen 39 will prevent solid material from passing to the portions of the carburetor, and such solid materials will

tend to collect in the cavity 36, where they may be easily removed when the drain plug 40 is unscrewed. The construction just described provides a means for manually 5 opening the valve 26 so as to permit gasoline to flow into the float chamber independently of the operation of the float. This may be desirable under certain conditions, but it is not essential to this invention. A 10 drain plug 40 may be provided for this cavity 36 and it will be noted that such cavity extends downwardly below the gasoline inlet 35 so as to retain sediment therein. From the chamber formed by the casing 3 15 the gasoline is adapted to enter a plurality of orifices 41 (one of which is shown in the section) formed in the fitting 11 and to pass to the fuel supply nozzle through a small Venturi tube 42, the tapered upper portion 20 of which aligns with the flaring nozzle passageway 43.

As thus far described, it will be seen that when sufficient suction is provided by the engine, the gasoline will pass upwardly 25 through the nozzle either in the form of a fine spray or stream, or else it will be partially vaporized and completely fill the diverging tube 43, or else it will fill the diverging tube 43 in its liquid form. The 30 particular physical state that the gasoline will assume within the tube 43 obviously depends upon the suction exerted upon the upper end of such tube and the rate of flow of the gasoline through the lower portion 35 thereof. In any of the three methods that it may traverse such delivery nozzle, it is finally passed upwardly into the space between the orifices 17 and 14 and mingles with the air passing downwardly through the carburetor and is drawn through the delivery duct 6 together with the air with 40 which it has been intimately mixed. It will be noted that at high engine speeds the jet velocity is higher because the passage 45 43 may become partially or wholly emptied and the full hydrostatic head of the fuel, due to the submerged positioning of the nozzle, becomes effective at the entrance to the nozzle. At slower engine speeds the 50 jet velocity is lower, as the passageway 43 may become completely filled with fuel and the hydrostatic head becomes less effective. It will be further noted that the bottom portion 55 of the throttle valve may end a slight distance above the upper points of the triangular projections 13. By proportioning and shaping the openings 17 and 14 and nozzle and contracted upper portion 5" in the manner shown and described, it has been 60 found that for varying engine speeds, varying loads, and for varying settings of the throttle, the mixture remains substantially constant. That is to say, an increase or decrease in the speed of the engine does not 65 alter the proportion of the gasoline to the

air nor does a change in the setting of the throttle alter such proportion.

In the carburetor of the present invention, a substantially constant mixture is maintained by providing openings controlling the different passages, of such a type that they have different characteristics. Thus, when the velocity of air rises, an inordinate increase in the fuel does not result for the reason that the coefficient of discharge for the orifices 17 rises as the velocity rises. When the velocity of the air falls the coefficient of discharge decreases, the orifices 17 offering an increased resistance to the passage of the air, thereby maintaining a sufficient partial vacuum. The orifices 14 and fuel nozzle are so sloped and proportioned that the quantity of fuel supplied will vary substantially in accordance with the quantity of air passing there- 75 through.

Consider the throttle valve as almost closed and moving in a direction to open the valve. It will be seen that as the valve moves towards open position, the area uncovered for the openings 14 increases at an increasing rate, while the area uncovered for the openings 17 increases at a decreasing rate. In other words, for each unit of travel of the valve towards open position, the 80 increment of area increased for the openings 14 is larger than the preceding increment of increase of area, and conversely each successive increment of increase in area for the openings 17 is less than that immediately preceding. 85

When the throttle valve of a carburetor is suddenly opened, it is sometimes found that the suction which has been drawing the fuel into the carburetor is temporarily insufficient until the engine has picked up 90 sufficiently in speed to guard against such temporary insufficiency. I believe the temporary deficiency above referred to to be caused by the following conditions: 95

In the first place, the flow of fuel through passage 43 is introduced primarily by a difference in pressure within the carburetor and exterior thereto. The pressure exterior to the carburetor is, of course, constant 100 since it is atmospheric pressure. The comparatively low pressure existing within the carburetor is proportionate to the demands of the engine and to the extent to which the suction of the engine is relieved by the admission of air through port 17 for a given setting of the throttle valve and for a given engine speed the pressure within the carburetor will obviously remain constant. If 105 the throttle valve setting remains unchanged, pressures in the carburetor can be altered only by a change in engine speed such as might be occasioned by a change in the load upon the engine. Similarly, 110 when the throttle valve is first opened, the 115 120 125 130

first effect of the opening of the valve is to relieve the low pressure existing within the carburetor. Until the engine is caused to accelerate, there will be no increased demand on the part of the engine, and consequently the more ready admission of air through the port 17 of the valve will tend to decrease the suction existing therein. In a carburetor of this design there would not, without an auxiliary fuel feed, such for example as that hereinafter to be described, be any tendency for the engine to accelerate, since the first effect produced by the opening of the throttle valve is, as above stated, to relieve the vacuum within the carburetor, and thereby actually to decrease the suction upon the fuel nozzle. Engine acceleration requires a supply of fuel additional to that which is required to drive the engine at the speed from which it is to accelerate. In ordinary carburetors the mixture is ordinarily maintained at all times richer than the theoretically perfect mixture, and the surplus amount of fuel is available for use in the production of engine acceleration. It is my aim to use an approximately perfect mixture at all times, and, therefore, at the moment the throttle valve is opened, there is no fuel being admitted to the carburetor beyond the amount which is absolutely necessary for the work of the engine under conditions existing at that time.

Therefore, when the throttle and air inlet valve is first opened and the suction within the mixing chamber is relieved by the increased efficiency of air flow through the enlarged opening 17, there will be no corresponding stimulation of flow through the fuel passage 43 until the flow of fuel through said passage is stimulated by some such fuel accelerator as that which is about to be described. Obviously, as soon as the additional quantity of fuel reaches the mixing chamber adjacent ports 14, it will be taken up by the air admitted through port 17 and will at once reach the engine, thereby causing that acceleration which alone is capable of restoring pressure conditions within the carburetor to their proper relation to the degree to which ports 17 are open. It will particularly be noted that the means hereinafter to be described does not destroy the constant proportions of the mixture, but, on the contrary, maintains the mixture proportions by supplying fuel at such times as the fuel supply would otherwise become diminished in proportion to the air admitted.

On the other hand, when the throttle valve is closed, the auxiliary means hereinafter to be described will operate to diminish fuel flow through the nozzle, thereby tending to preserve the mixture constant. It will be seen that the initial closing movement of the throttle valve will at once com-

mence to cut off the supply of air admitted through ports 17, or, rather, to increase the suction within the mixing chamber by decreasing the size of ports 17 and thereby decreasing the efficiency of said ports for air delivery. The engine, however, will not at once lose its speed and will therefore, for a time, continue to exert a suction demand out of proportion to the new position of the throttle valve. This suction demand would, but for the auxiliary means above referred to, produce an excessive flow of fuel through the delivery passage 43. The auxiliary means, by withdrawing a portion of the fuel on its way to said passage and by reducing, in effect, the hydrostatic head which forces the fuel into said passage, will prevent the tendency for acceleration of fuel flow which would otherwise exist.

Auxiliary means have been provided by this invention, which are actuated by the throttle valve and respond instantly to the movement of the throttle valve and serve to temporarily enhance the delivery of fuel when such throttle valve is suddenly opened. These means comprise an upper cylinder 44 within which fits a piston 45, provided with piston rings 45', which piston is connected with or is formed integrally with the stem 21 which operates the throttle valve. An inner cylindrical casing 46 extends downwardly on the inside of the hollow piston and serves as an additional means for securing an airtight joint for the piston and also for improving its operation. It will be noted that the air delivery pipe 47 extends downwardly at 48 to the bottom part of the cylinder. This is for the purpose of causing any gasoline that might lodge within the hollow piston to be discharged through such pipe when the piston is raised and the air above the piston compressed. It is not known exactly what causes the hollow piston to fill with fuel. Actual tests, however, have shown that it does so fill. It is presumed either that the fuel gradually absorbs the air in a system of passages of which the piston is a part, or else that at each operation of the throttle valve which produces air pressure in such system, a portion of the air may leak out through the packing rings of the piston so that upon the next closing movement of the throttle valve the fuel in said system will be drawn nearer to the piston in compensation for the amount of air which has thus escaped. The compressed air (or fuel) passes through the pipe 47, through the pipe 49, through the duct 50, to an annular cavity 51 formed between the cylindrical member 8 and the fuel nozzle 9. This cavity 51 serves as an additional temporary reservoir for gasoline which is admitted thereto through an opening in the fitting 11 which opening communicates with the lower portion of the

cavity 51 and is closed by a fluted check valve 52. A convenient means of retaining the check valve is provided by inserting a pin 53 in the upper flange 54 of the fitting 11 such pin being retained in position by the cylindrical portion 8. Three ducts 55 (one of which is shown) pass through the fitting 11 and serve to discharge the gasoline from the cavity 51 into the cavity 56 from which it passes through a nozzle 57 which has a minute opening in its upper end aligning with the passage 43 in the fuel nozzle and spaced a slight distance therefrom. The check valve 52 is not absolutely essential to the operation of the device as it is obvious that some gasoline will pass into the chamber 51 through the passages 55. A convenient means of retaining the cylinder 44 in place is to provide a saw cut or split in the portion 1 which saw cut extends into the space occupied by the cylinder 44. The opposed faces at this slit may be drawn towards each other by a cap screw passing through the opening 58.

The action of this auxiliary device is as follows: Assuming that gasoline is in the reservoir formed by the casing 3 and also that gasoline is in the cavity 51, it will be seen that a sudden upward movement of the throttle valve serves to compress the air in the upper cylinder, which air pressure acts upon the surface of the gasoline in the cavity 51 forcing it through the ducts 55, cavity 56, up through the nozzle 57. This fine, high speed stream of gasoline entrains additional gasoline in the fuel delivery nozzle and causes an augmented flow to occur, thereby offsetting any diminution in the flow of the gasoline which might be incident to a sudden opening of the throttle valve. Several seconds elapse before the augmented flow ceases, whereby time is given for all of the cylinders to receive this additional charge, thereby maintaining the substantial constancy of the mixture until the level of fuel in the nozzle 43 reaches its new position and said nozzle commences its normal function at the new engine speed.

The economy of operation is improved for the reason that the augmented flow does not occur under normal or steady running conditions, but only when there is a sudden need for it. In other words, the fuel nozzle is designed for the best economy and is not altered in size, but is caused to temporarily allow an increased flow by auxiliary means. When the throttle valve is suddenly closed the flow through the fuel nozzle is decreased by the auxiliary device, as the flow through the auxiliary nozzle 57 is reversed.

This auxiliary device is also of service in starting for the reason that when the engine is being slowly rotated, the velocity of the gases through the carburetor may not

be such as to entrain or volatilize a suitable quantity of gasoline to provide a proper explosive mixture. Therefore, before starting, the throttle valve is operated three or four times which causes the auxiliary apparatus to function, thereby causing an augmented flow of gasoline, partially or entirely filling V grooves 14. With the throttle valve in partially closed position, the gasoline is then above the lower end of the throttle valve cylinder 19 whereby the incoming air is caused to pass through the gasoline when the engine is rotated.

It may be that the operation of my improved carburetor will most easily be understood if I explain in detail the considerations, both practical and theoretical, which led to the design and particular arrangement and proportion of parts disclosed herein.

The initial calculations and tests upon this carburetor were made with a wide open throttle, and having worked out a carburetor having theoretically perfect performance under various conditions of speed with wide open throttle, the carburetor was modified to retain its principle of operation while fitting it for similarly efficient operation under varying throttle settings. It is not to be understood that the various features were worked out exactly in the order in which they are hereinafter described, since in practice it was necessary to test and re-test each feature with others until the underlying principles were determined to be sound, and the whole was functioning properly.

First of all, the passage 6 was designed to fit the inlet manifold of the internal combustion engine with which the tests were made. The metering nozzle 42 was then chosen and was so designed and proportioned as to be capable of supplying at wide open throttle the amount of fuel required to carburet the air which would be admitted through ports 17 at maximum air speeds. The position of the Venturi plug 42 was later found to have a modifying influence upon the discharge of said plug which required a change in the size of plug which was at first thought necessary. The particular position of plug 42 which was ultimately adopted resulted from the choice of a particular included angle between diametrically opposite portions of the wall of passage 43, and resulted also from a preferred ratio of the cross sectional area of said passage at its upper end to the cross sectional area of the Venturi opening in the plug 42 at its smallest point.

It has been determined by scientific experimenters that the most efficient Venturi passages have at their discharge ends an included angle of approximately 5 degrees. For this reason the passage through the

Venturi plug 42 was so constructed. In order that the fuel delivered through the Venturi opening in plug 42 might continue its flow through passage 43 without unnecessary eddy currents, said passage was designed to continue the lines of the discharge end of the Venturi opening as shown. Thus, the walls of the passage also have an included angle of approximately 5 degrees.

It is my theory that the breaking up of the fuel into small particles is facilitated by causing the fuel to traverse a passage of the type shown at 43 in which the cross sectional area progressively becomes greater at a constant rate. It is my belief that the fuel can be most perfectly atomized (or broken up as aforesaid) if it is led through a passage of the type shown at 43 to a point in said passage where the cross sectional area thereof bears the peculiar ratio with respect to the cross sectional area of the smallest part of said passage that a gas bears to the liquid from which it can be formed. Consequently, I so designed passage 43 that a body of fuel disposed in the smallest part of the opening through the Venturi plug 42, and occupying a unitary axial distance in said plug would, if carried to the discharge end of passage 43 with the several constituent particles of said fuel in their same relative positions, just fill the upper end of said passage. There is obviously a tendency for fuel moving through a passage of said type to progressively expand and fill the space between the walls which confine it. A liquid can not so expand. Consequently, if a body of fuel disposed in the throat of the Venturi opening of plug 42 should follow the tendency aforesaid it would change in its traverse of passage 43 from a liquid substantially to a gas, or to relatively widely separated particles.

My experiments indicate that the fuel does not follow the tendency aforesaid under all conditions and that in fact it does not become a gas under any conditions under which I have been able to observe it. At high fuel speeds, however, I have determined that the fuel is very thoroughly atomized during its traverse of passage 43, and I ascribe this thorough atomization to the particular construction of the passage, in view of the considerations above noted.

The cross sectional area of the upper end of passage 43 having been thus proportioned to the cross sectional area of the smallest part of the Venturi opening through plug 42, and the relative locations of said plug and the upper end of said passage having been determined by the theoretical considerations aforesaid, it was necessary next to provide a throttle device capable when open of permitting the passage of the maximum desired quantity of mixture. I also considered it desirable so to shape the throttle valve openings 14 that such openings might increase

in area proportionately to the square of the distance through which the throttle valve was to be moved in opening. Furthermore, in order to have as few variable factors as possible affecting the operation of my carburetor, I desired to provide ports which would have comparatively constant co-efficient of discharge, relatively unaffected by changes in velocity of the mixture passing therethrough. It was my theory also that by a peculiar design of throttling device, I might facilitate the mixture of air and fuel.

The ports 14 were designed with all of the above considerations in view. Their shape and their relation to the tubular portion 19 of the throttle valve is such that as the throttle valve is moved upwardly to open said ports, the area of the ports will increase as the square of the distance through which the throttle valve is moved. The capacity of the ports is such, if the dimensions shown in the drawing forming a part of this application are followed, that such ports are capable of supplying the full desired quantity of combustible mixture. The peculiar form of the pyramidal projections 13 between said ports is determined with reference to the co-efficient of efflux of the ports, and it was my object in designing the elements 13 so to form them that the co-efficient of efflux of said ports would remain substantially constant, thereby relieving the carburetor of one possible variable factor which might affect its performance. The elements 13 were also designed as shown to conform to my theory that their peculiar shape facilitates the mixing of air and fuel adjacent the outlet to the passage 43.

Except as otherwise explained herein, the operation of the Venturi metering plug 42 and the operation of the mixture ports 14 are believed to be both substantially constant in the sense that the co-efficient of efflux of a properly designed Venturi passage is substantially constant, and, so far as I have been able to ascertain, the co-efficient of efflux of the openings 14 is also substantially constant. I regard it as an advantage to have few variable factors affecting the operation of a carburetor. The air admission ports 17, which are simultaneously variable in size as aforesaid, are adapted primarily to control the operation of the entire carburetor at any given throttle setting. Their combined area, as shown, is such that with due consideration for their co-efficient of discharge, they are capable of permitting the free passage of the maximum desired quantity of air to be carbureted and drawn through the throttle openings 14. The fact that the apertures 17 are disposed in a relatively thin plate adapts them under well known physical laws to have a variable co-efficient of discharge thereby providing a factor regulative of the

degree of suction which will exist within the mixing chamber portion of the carburetor in proportion to any given degree of throttle opening. If it were not for the 5 variable co-efficient of discharge of the openings 17, it will be obvious that with an unchanged throttle setting, the flow of air would vary in accordance with variations in the air head which induces flow; but the 10 variation in flow would not be exactly proportional to the variation in head.

As the air head is increased, whether by the increased speed of the engine or otherwise, the flow of air will be correspondingly 15 increased, but, due to the resistance offered to the passage of the air by the ports through which it is obliged to pass in traversing the carburetor, the increased flow can occur only at the expense of air density so 20 that if the co-efficient of discharge of each port remains constant the density of the air will gradually decrease. Thus, the flow of air as measured by weight will not be exactly proportional to the change of air head 25 which induces that flow.

The above facts, with regard to the flow of air, do not hold with regard to the flow of liquid. The increase in head, such as 30 might be caused by increased suction at the outlet end of the carburetor, will cause a variation in liquid flow which will tend to be exactly proportional to the variation in head. Thus, if one relatively low air head be taken as unity and the fuel supply passage is so proportioned to the air inlet ports 17 that at this unit head there will be 35 fifteen units of air flow through port 17 in proportion to one unit of fuel weight, then, as the air head is increased to five units of head the fuel flow will tend to increase in exactly the same proportion to produce a flow of five units of fuel. But, due to the law aforesaid, the air flow will not 40 maintain the proportion, but, in the absence 45 of a properly designed port at 17 will fall below the 75 units of air.

In order to overcome this tendency the ports 17 are so constructed as to take advantage of the law relating to the flow of 50 gases through orifices in thin plates. Thus, the resistance offered by ports 17 to air flow through said ports decreases as the rate of flow increases, the air flows through said 55 ports without change in density, and thus the air-fuel mixture is maintained substantially constant.

I have found, however, that at high air speeds the co-efficient of discharge of orifices 17 does not become sufficiently increased to counter-act a tendency for the air to become rarer at such speeds. Accordingly, I designed the constricting wall 5", and by experiment have found that it 60 exerts a modifying effect upon the variation of co-efficient of discharge of ports 17,

whereby at relatively high air speeds the co-efficient of discharge of said ports will be relatively greater with respect to their co-efficient of discharge at low air speeds than would be the case in the absence of the 70 constricting wall 5". It should be noted, however, that the wall 5" does not constrict air flow in the ordinary sense of the term since the area of the opening bounded by said wall is sufficient large to permit the 75 unimpeded flow of the maximum quantity of air which can, under like circumstances, pass through the ports 17.

The operation of the fuel pump in regulating fuel flow under abnormal conditions 80 for the purpose of maintaining the mixture substantially constant has already been described and will not be repeated at this point.

It will be seen from the foregoing that I 85 have designed a carburetor which is adapted to maintain a substantially constant mixture under all working conditions. By way of summary, it may be noted at this point that for fixed throttle positions the carburetor 90 automatically compensates for changes in air head solely through the variable co-efficients of discharge of ports 17 as modified by the presence of wall 5", all other factors within the carburetor being so designed as 95 to be constant or substantially so; and that for those abnormal conditions which are created at the time when the throttle valve member is adjusted simultaneously to open or close ports 14 and 17, compensation is 100 made by the pump, which maintains the mixture constant until the air flow becomes stabilized and reaches the rate corresponding to the areas of the particular openings afforded by the valve in its new setting. 105

Although the relative sizes of the various ports, passages, and openings in this carburetor are disclosed in their proper proportions in the accompanying drawing, 110 I will nevertheless state herein what such sizes are in order that those skilled in the art may duplicate this carburetor with the least possible degree of difficulty. The diameter of the Venturi passage through plug 42 at its throat is .039 inch. The area of passage 43 at its upper end is .0818 square inch. The length of the passage 43 is 3 inches to the end of the plug 42, and for every inch variation in the length of said 115 passage the diameter of the throat of the Venturi opening through said plug 42 must be changed approximately .001 inch. If the plug is moved upwardly toward the upper end of the passage, the diameter of said 120 throat must be increased, and if the plug is moved downwardly the diameter of the throat may be decreased, due to the change in hydrostatic head.

The combined area of the ports 14 is 130 1.2272 square inches at wide open throttle.

As shown, there are six of such ports, and the altitude of each triangular opening from the base to the apex thereof at wide open throttle is $\frac{5}{8}$ of an inch. The combined area of ports 17 is 1.4498 square inches at wide open throttle. There are eight of such ports, and the altitude of each from the base to the apex thereof is .57206 inch. The base line of each is .6312 inch. The area of the annular space between the throttle valve and the wall portion 5" is 1.36355 square inches. I have found by experiment that a carburetor constructed in accordance with the disclosure in the drawings of this application can be used successfully upon different types of engines, within its capacity, without modification. I ascribe this fact to my carburetor design whereby the mixture of fuel and air is maintained constant so that a given quantity of air passing through my carburetor is always carbureted substantially to the same degree. Thus, irrespective of the engine requirements, within the capacity of the carburetor, an ideally perfect mixture or substantially such is supplied at all times, regardless of the quantity of mixture flow in a given space of time.

Furthermore, I have discovered by actual tests that an engine equipped with a carburetor constructed in accordance with the disclosure in the accompanying drawing will remain much cooler than when the same engine is equipped with any other make of carburetor with which I am familiar.

I claim:

1. A carburetor having means defining inlet and outlet ports of adjustable area, said means being adjustable to vary simultaneously the areas of said ports in proportions adapted to maintain the degree of vacuum between said ports proportionate to air flow in any given setting of said means, a fuel inlet leading to said carburetor with its discharge end exposed to said vacuum and having a normally substantially constant co-efficient of efflux, and a source of fuel supply under substantially constant head and arranged for fuel delivery through said inlet, whereby fuel flow will be proportioned to the degree of vacuum aforesaid and to the rate of air flow.

2. A carburetor having means defining inlet and outlet ports of adjustable area, said means being adjustable to vary simultaneously the areas of said ports in proportions adapted to maintain the degree of vacuum between said ports proportionate to air flow in any given setting of said means, a fuel inlet leading to said carburetor with its discharge end exposed to said vacuum and having a normally substantially constant co-efficient of efflux, and a source of fuel supply under substantially constant head and arranged for fuel delivery through

said inlet, whereby fuel flow will be proportioned to the degree of vacuum aforesaid and to the rate of air flow, said inlet port having a co-efficient of efflux variable with the rate of flow at any given setting of said means, whereby the density of air entering said port will be maintained substantially constant.

3. A carburetor comprising a main casing having air inlet and mixture outlet passages, a throttle valve in the form of a sleeve, controlling spaced triangular ports at the air inlet and mixture outlet passages, said throttle valve adapted to vary the opening of the ports in different amounts for each setting of said throttle valve, a source of fuel supply, and a Venturi fuel nozzle of substantially constant co-efficient of discharge having a submerged entrance and communicating with the space between the ports.

4. A carburetor comprising a casing having air inlet and mixture outlet passages; a throttle valve provided with air and mixture controlling portions, said portions and the casing adjacent thereto being formed and adapted, during the opening movement of said valve, to enlarge progressively the air passage with decreasing increments of change and to enlarge progressively the mixture passage with increasing increments of change; a source of fuel supply; a Venturi nozzle adapted to receive fuel under pressure from said source; and a passage leading from said nozzle to the interior of said carburetor between said air and mixture passages, said last mentioned passage having its cross sectional area expanded at a constant rate in the direction of fuel flow therethrough to a diameter having a maximum fuel vapor capacity proportioned to the maximum capacity of said air inlet passage substantially in the proportions of mixture desired.

5. A carburetor comprising a casing having an intake passage therein, a throttle valve, means co-operating with the throttle valve to form a mixture outlet port having a substantially constant co-efficient of discharge and an air inlet port with a co-efficient of discharge variable in proportion to air speeds; fuel supply means having a substantially constant co-efficient of discharge leading to said carburetor.

6. A carburetor comprising a casing, a valve member therein, said casing and said valve member being formed to provide air inlet and mixture outlet ports variable by the operation of said member with inversely varying increments of change, a Venturi fuel supply passage communicating with said carburetor and having a substantially constant co-efficient of efflux, fuel supply means leading to said passage with normally substantially constant hydrostatic head,

- and means for varying the effective hydrostatic head of said means during the opening and closing throttle movements, whereby to offset the effect of the opening of the 5 air inlet valve in advance of any increasing flow through said mixture outlet passage.
7. A carburetor including a casing, a valve member movable within said casing, said valve member and casing being formed 10 to provide air inlet and mixture outlet ports variable by the movement of said valve member with inversely varying increments of change, said mixture outlet port being formed to have a substantially constant co-efficient of efflux and said air inlet port being formed to have a co-efficient of efflux varying in proportion to air flow therethrough, a chamber, means for maintaining fuel at a substantially constant level 15 therein, a Venturi jet at a level below the level of fuel in said chamber and in communication with the interior of said chamber, a passage between said jet and the interior of said carburetor formed to provide cross sectional areas expanding at a constant rate in the direction of fuel flow, and means 20 operatively connected with said throttle for varying the effective hydrostatic head of fuel at said Venturi nozzle, whereby said fuel is accelerated positively during the opening movement of said throttle and negatively during the closing movement of said 25 throttle.
8. In a carburetor having an air inlet port with a co-efficient of discharge variable in proportion to air flow and a mixture port having a substantially constant co-efficient of discharge, means for simultaneously varying the areas of said ports at a variable 30 rate with inversely varying increments of change, and fuel supply means including a passage provided with a Venturi throat in communication with the interior of said carburetor.
- 45 9. A carburetor including a casing provided with inlet and outlet passages, a Venturi metering nozzle provided with a flaring discharge passage in communication with the interior of said carburetor, a source of fuel supply normally maintained at a level above the throat of said nozzle, a plurality of pyramidal projections spaced concentrically about the discharge end of said fuel passage and providing triangular ports communicating with the discharge passage of said carburetor casing, a sleeve valve movable within said casing and provided with triangular ports, said sleeve valve being adapted to 50 close and open the first mentioned ports and said casing being adapted, upon the movement of said valve, to close and open the ports therein, said last mentioned ports having a variable co-efficient of discharge.
- 55 60 65 70 75 80 85 90 95 100 105 110 115 120 125 130 135
10. A carburetor comprising a casing having air inlet and outlet passages communicat- ing therethrough, a throttle valve within said casing having two component parts respectively controlling said inlet and outlet passages, and a Venturi fuel nozzle communicating with the space between the component parts of the throttle valve, said parts being arranged to control the areas of the inlet and outlet passages with varying rates of change, such areas as are controlled by the valve and the area of the fuel passage being so formed and proportioned that in the various positions of the valve at any given setting thereof the capacity of the fuel passage will be proportioned to the capacity of the inlet passage in substantially the desired ratio to air and the combined capacity of the inlet passage and fuel passage will be substantially equal to the capacity of said discharge passage.
11. In a carburetor having passages therethrough, the combination of a compound throttle valve adapted to simultaneously constrict the passages at separated points and defining ports at said points, one of which has a substantially constant co-efficient of efflux and the other of which has a variable co-efficient of efflux, a fuel nozzle communicating with the space between the said points, whereby fuel is drawn into said space by the partial vacuum produced therein, the relative constriction at the separated points being such that the supply of fuel varies substantially in accordance with the quantity of air passing through said carburetor, and means to temporarily compensate for a sudden change in the setting of the throttle valve.
12. In a carburetor, the combination with a casing having a passage therethrough providing inlet and outlet ports, of a throttle valve co-operating with said ports, and a fuel supply duct communicating with said passage intermediate said ports, said inlet port having a variable co-efficient of discharge approaching maximum efficiency as the flow of air therethrough approaches a maximum, and the co-efficient of discharge of said outlet port being substantially fixed at approximately the maximum efficiency of discharge toward which said inlet port approaches.
13. A carburetor including the combination with a casing having a passage therethrough, of a series of projections formed to provide a first port in said passage having a substantially constant co-efficient of efflux, means providing a second port in said passage having a variable co-efficient of efflux, means for simultaneously varying the areas of said ports with varying increments of change, a Venturi nozzle provided with an elongated discharge passage leading to said casing passage, the discharge end of said Venturi passage having a capacity proportioned to the maximum capacity of said

second port in substantially the proportion of fuel to air desired in the efflux from said carburetor, and the forms of said first and second ports being determined to control the degree of sub-atmospheric pressure at the Venturi passage and so calculated for different positions of the throttle valve that at any given setting, the capacity of said first port will exceed the capacity of the second port by the amount of fuel vapor required to maintain the desired ratio of fuel to air as aforesaid.

14. A carburetor including a casing having a passage therethrough, means providing a mixture port having a substantially constant co-efficient of discharge, means providing an air port having a co-efficient of discharge variable in proportion to air flow, means for simultaneously adjusting the areas of said ports with varying increments of change, a Venturi fuel passage discharging into said casing passage in the path of air moving between said ports, a fuel chamber in communication with said Venturi passage and adapted to maintain fuel at a level above the throat of said Venturi passage, a jet aligned with said venturi and communicating therewith, and a pump connected with said adjusting means and communicating with said jet.

15. A carburetor having a passage there-

through with inlet and outlet ports of variable area at spaced points in said passage and formed to have variable and substantially constant co-efficients of discharge respectively, and a fuel inlet passage communicating with said first mentioned passage between said ports and having a Venturi throat formed therein and a substantially constant co-efficient of discharge, and means for varying the areas of said inlet and outlet ports in predetermined proportions which are adapted to produce a degree of vacuum adjacent said fuel passage proportioned to the air flow in any given setting of said means.

16. In a carburetor, the combination of a main throttle valve adapted to constrict the flow of air through the carburetor at two spaced points, fuel supply means entering the space between such points and controlled by the partial vacuum created in such space, said carburetor having orifices, adjacent the inlet portion, which have a co-efficient of discharge increasing with increasing velocity, said fuel supply means having an orifice through which the fuel passes, which has a substantially constant co-efficient of discharge, whereby a substantially constant mixture is maintained.

In testimony whereof I affix my signature.
WILLIAM SCHOOF.
